UNITED STATES PATENT OFFICE.

WILLIAM S. OSBORNE, OF HYDE PARK, MASSACHUSETTS.

PNEUMATIC SEPARATOR SYSTEM.

No. 878,665.

Specification of Letters Patent.

Patented Feb. 11, 1908.

Application filed April 9, 1906, Serial No. 310,734.

To all whom it may concern:

Be it known that I, WILLIAM S. OSBORNE, a citizen of the United States, residing at Hyde Park, in the county of Norfolk and 5 State of Massachusetts, have invented certain new and useful Improvements in Pneumatic Separator Systems; and I do hereby declare the following to be a full, clear, and exact description of the invention, such as 10 will enable others skilled in the art to which it appertains to make and use the same.

This invention relates to improvements in pneumatic separator systems.

The object of the invention is to produce 15 an improved pneumatic system for grading and separating granulated and pulverized materials, particularly such as are of an abrasive character, in which wear upon the apparatus is reduced as far as possible, and 20 in which provision is made for conveniently adjusting the apparatus to grade or separate material in any required manner.

Other objects of the invention will be noted in connection with the description of 25 the illustrated embodiment of the invention.

The invention consists in the improved pneumatic separator system hereinafter described as defined in the claims.

In the drawings Figure 1 is an elevation 30 of a pneumatic separator system embodying the present invention and Fig. 2 is an elevation partly in section on a plane at right angles to that of Fig. 1.

The illustrated embodiment of the invention 35 comprises a pneumatic separator, a dust collector, and a blower, arranged in circuit so as to form a closed system and use the same body of air repeatedly. The pneumatic separator, indicated generally by the 40 reference character 1, comprises a casing having the general form of a segment of a circle, as shown in Fig. 2, and provided with two parallel vertical walls 2, as shown in Fig. 1 and a circularly curved top 3. The air is 45 forced into the separator through an air inlet 4 at the bottom and escapes through an air outlet 5 at the top whence it is conveyed by short trunk to the dust collector 6. Within the air inlet 4 is mounted a feed disk 50 7 journaled upon a shaft in a bearing 8 and rotated by bevel gears 9 connected with a pulley 10 which is actuated by any suitable source of power. The gears are inclosed in a 55 casing 11 to protect them from dust. Directly about the disk 7 is an inlet pipe 12

through which material to be separated or graded is introduced. A trunk 13 extends downwardly from the bottom of the separator casing and is provided with interior partitions 14 between which and the walls of the trunk passages 15 are formed adjacent to the sides of the trunk. The lower end of the trunk is provided with an outlet 16, and an air blast pipe 17 enters the trunk and directs a current of air upwardly through the air inlet 4. When the separator is in operation the feed disk 7 is rapidly rotated and throws the material delivered by the feed pipe 12 across the air inlet 4 where it is entrained by the upward blast of air and raised into the casing of the separator. The dust and lighter particles are immediately carried away into the dust collector 6 by the current of air, while the heavier particles either fall directly through the air inlet 4 and out through the outlet 16 or remain suspended for a while in the air current and finally, coming in contact with the walls of the separator, slide down the walls and escape through the outlet 16.

To provide for adjustment of the separator to secure the desired effect upon the material the separator is provided with two adjustable walls 18 pivoted at their lower extremities, as shown in Fig. 2, to the tops of the partitions 14 and provided with two adjusting rods 19, which are pivoted to the walls 18 at their inner ends and pass out through slots in the outer walls 20 of the casing. Teeth on the lower sides of the adjusting rods 19 normally engage the lower ends of the slots so as to hold the walls 18 in adjusted position, and cover plates 21 sliding in ways 22 on the walls 20 closely embrace the rods 19 and prevent the escape of air or dust. When it is desired to adjust the walls 18 the outer ends of the rods 19 are raised, together with the slides 20, so as to disengage the teeth, and the rods may then be pushed in or pulled out. By this adjustment the width of the air passage in the separator between the walls 18 is varied, and thus the velocity of the air current at this point is varied and the separator may be made to grade material to different degrees of fineness. When it is desired to carry only the finest particles into the dust collector the walls 18 are moved apart so as to increase the space between them and reduce the velocity of the air current, and under these conditions only the finest particles

will be sustained by the air current and carried into the dust collector. When it is desired to carry coarser particles into the dust collector the walls 18 are adjusted closer together. Any dust escaping to the spaces behind the walls 18 is carried off by the passages 15.

The dust collector 6 may be of any suitable form, that shown being of the familiar 10 centrifugal type, which need not be particularly described as its construction is well known. The blower 23 may also be of any suitable form, that shown being the familiar 15 centrifugal type. The relative arrangement of the separator, the dust collector and the blower is such that no material is passed through the blower, the material being delivered to the air blast after it issues from the blower and being entirely abstracted from 20 the air by the separator and the dust collector before the air is returned to the blower from the latter by the air pipe 24. This feature is novel, so far as the inventor is informed, in a closed pneumatic separator system, and 25 it is a feature of importance where the material to be operated upon is of an abrasive character such as might injure the blower by violent contact with the rapidly moving blades, or of a character which would tend 30 to cause it to clog the casing of the blower or to collect upon the arms thereof.

The air pipe 24 is provided with equalizing vents 25 connected with cylinders of wire 35 gauze 26 to prevent the escape of dust. The object of these vents is to permit the entrance or escape of air when necessary to equalize the air pressures within and without the apparatus. It is to be noted that these air vents are so located that the air separator 40 is caused to operate by means of a blast of air under pressure as distinguished from a current of air produced by suction as in the previously proposed device of this character; that is to say, any vacuum in the air pipe 24 45 will be at once neutralized by the entrance of air through the vents 25. This is a feature of importance in the present construction, and conduces to the successful operation of the apparatus. As material is introduced 50 through the feed pipe 12 and accumulates in the separator, it causes a back pressure and accumulation of air in the blast pipe between the blower and the separator owing to the resistance offered by the body of material in 55 the separator to the passage of air therethrough, and this results in a partial vacuum in the air pipe 24 and an inflow of air through the vents 25 to restore the atmospheric pressure in the air pipe. Upon any diminution 60 in the weight of material suspended in the separator, a reverse action takes place; that is to say, the pressure between the blower and the separator diminishes and an outflow of air occurs at the vents 25.

65 The present invention is not limited to the

details of construction and operation of the illustrated embodiment thereof, but may be embodied in the forms broadly defined in the claims.

Having now described the invention, what 70 is claimed is:—

1. A pneumatic separator system, having, in combination, a pneumatic separator provided with laterally adjustable side walls, a dust collector, and a blower connected in 75 circuit and provided with an equalizing vent between the dust collector and the blower, and means for introducing material into the air after it is discharged from the blower, substantially as described. 80

2. A pneumatic separator, having, in combination, a casing provided with an air inlet at the bottom and an air outlet at the top, and adjustable partitions pivoted at their lower ends in the casing and provided with 85 means for holding them in adjusted relative positions, the casing being provided at the bottom outside of each adjustable partition with an outlet for material leaking around the edges of the partition, substantially as de- 90 scribed. 95

3. A pneumatic separator system having, in combination, a blower, a separating chamber connected with the outlet therefrom, means for introducing material between the 95 blower and the separating chamber, and a dust collector connected with the separating chamber and provided with an air outlet connected with the inlet to the blower, the separating chamber being adjustable to 100 vary the area of its cross section, substantially as described.

4. A pneumatic separator system having, in combination, a pneumatic separator through which the air passes upwardly, a 105 dust collector, provided with laterally adjustable side walls, and a blower, connected in circuit, the separator having provision for admission of air under pressure at the bottom and the introduction of material to be sorted 110 in a direction opposite to the direction of admission of the air, such separator acting to remove coarser particles of the material to be sorted, and the dust collector receiving the air from the outlet of the separator and operating to remove the finer particles of material, the air outlet of the dust separator being connected with the blower, the arrangement being such that only the fine impalpable powder is returned to the blower where- 115 by the blower is preserved from the destruc- 120 tive wear of the material to be sorted. 125

5. A pneumatic separator having, in combination, a chamber provided with laterally-adjustable upright walls affording a vertical 125 air passage of variable cross-section, a blower delivering air under pressure at the bottom of the chamber, and means for introducing material at a place in the air current so produced where it is completely surrounded by 130

air and permitting it to fall against the annular upward current of air, substantially as described.

6. A pneumatic separator system having, in combination, a pneumatic separator, a blower having its outlet connected with the separator, a dust collector receiving air from the separator, and a pipe provided with an air vent and connecting the outlet of the dust 10 collector and the inlet of the blower, the separator comprising a vertical passage provided with laterally-adjustable walls between

which the air flows upwardly, and means for introducing material into the center of the air current at the bottom of the separator 15 and permitting it to fall against the air current, substantially as described.

In testimony whereof I affix my signature in presence of two witnesses.

WILLIAM S. OSBORNE.
